UNITED STATES PATENT OFFICE.

PAUL S. SMITH AND ALBERT FORBES, OF ROCKY MOUNT, NORTH CAROLINA, AND
WILLIS L. SIMMONS, OF RICHMOND, VIRGINIA.

SHADE DEVICE.

Application filed February 27, 1922. Serial No. 539,698.

To all whom it may concern:

Be it known that we, PAUL S. SMITH and ALBERT FORBES, citizens of the United States, residing at Rocky Mount, in the county of Edgecombe, in the State of North Carolina, and WILLIS L. SIMMONS, a citizen of the United States, residing at Richmond, in the county of Henrico, in the State of Virginia, have invented certain new and useful Improvements in Shade Devices, of which the following is a specification, reference being had to the accompanying drawings.

This invention relates to a shade device for use in connection with headlights, and more particularly to a shiftable control plate for controlling the scope of the rays from the headlight.

An important object of the invention is to provide an improved shiftable plate. A further object of the invention is to provide an improved operating mechanism therefor.

A still further object of the invention is to provide a headlight control of this character which may be readily installed, which is simple in construction and operation, durable in service, and a general improvement in the art.

These and other objects we attain by the construction and arrangement shown in the accompanying drawings wherein for the purpose of illustration is shown a preferred embodiment of our invention and wherein like reference characters designate like parts throughout.

In the drawings:

Figure 1 is a fragmentary side elevation showing an automobile equipped with a shade apparatus and operating mechanism therefor constructed in accordance with our invention;

Figure 2 is an enlarged front elevation showing the shade devices in closed position upon the headlights; and

Figure 3 is an enlarged sectional view showing the operating mechanism for the shade device.

Referring now more particularly to the drawings, the numeral 10 indicates the headlights of a vehicle upon each of which is mounted, at the upper surface thereof, a bearing member 11 in which are rotatably disposed the ends of a shaft 12 extending transversely of the vehicle. To the ends of this shaft above each headlight are secured,

as by means of ears 13, control plates 14 each comprising a concavo-convex disk having the concave face thereof disposed toward the headlight and polished to form a reflector.

These disks are provided in what are the lowermost edges thereof when the same are in the closed position, as illustrated by the full lines in Figure 2 with a notch 15 permitting a portion of the rays to pass from the headlight downwardly and forwardly through a restricted area so as to light the ground immediately in front of the automobile, thus cutting off the glare from any approaching vehicle without cutting off the driving light or that portion of the light necessary to proper operation of the vehicle. When the plates 14 are fully open, the entire rays of the headlight pass out unobstructed, thus permitting the use of the full power of the headlight when desired or enabling the driver to cut down the rays of the headlight so as to permit a vehicle to pass without danger. The plates 14 may, of course, be arranged at any intermediate position between the full open and full closed positions so that rays may be governed at any point from the reduced area between the lines R and R' to the full ray position when the rays are distributed through an area indicated by the lines R and R'. The plates 14 are preferably provided with flanges 14^a which, when the plates are in the closed position, engage about the lens retaining rim 10^a of the headlight.

In order that light may be constantly shed upon the side of the road next adjacent which the vehicle is traveling, we provide the side of the plate arranged upon the headlight which will be disposed next adjacent the side of the road with a notched or cutout portion 16 in the outer side thereof so that the rays will be directed not only downwardly in front of the vehicle when the plate 14 is completely closed, but will be shed likewise to the side of the vehicle, illuminating the edge of the roadway and preventing danger of the driver of the vehicle passing from the road unwarned. Where a vehicle upon which our device is mounted is employed in a territory having right hand traffic and the rule is that the vehicle keep to the right hand side of the road, the right hand lamp will have its plate

14 thus constructed and where the rule is for left hand traffic, the plate of the left hand headlight will be so constructed.

The numeral 17 designates a shaft extending longitudinally of the vehicle and provided at its forward end with a spiral gear 18 secured thereto and meshing with a spiral gear 19 mounted upon the shaft 12. When the device is applied to the headlights of automobiles, this shaft will preferably extend through and be rotatably mounted in a nipple 20 mounted in the radiator 21 of the vehicle and having a fixed flange 22 abutting one face of the radiator and a removable flange 23 which, when in applied position, abuts the opposite face of the radiator. The opposite end of the shaft extends through a support 24, in the present instance indicated as the dashboard of the vehicle, and the shaft is provided with means, as collars 25, permitting limited end play of the shaft. Upon the dashboard a bearing 26 is provided through which the shaft extends and which has a shoulder and groove engagement, as at 27, with a rotatable nut 28. This nut has a recess 29 of greater size than the diameter of the shaft in which is disposed a spring 30 bearing at its forward end against the end wall of the recess and at its opposite end against a head 31 formed upon the shaft 17 and operating in the recess 29 or in an enlargement 29^a thereof, the head portion of the shaft being so formed that its engagement with the nut 28 prevents relative rotation thereof. It will be seen that by engaging the nut with the hand the same may be rotated withdrawing against the action of the spring to disengage the shoulder and groove connection of the nut and bearing and permitting rotation of the shaft, which rotation is imparted through the spiral gears 18 and 19 to the shaft 12, the spiral gearing providing a thrust receiving a great portion of the stress placed upon the shaft 12 by the plates 14 when in open or partly open position,

5 preventing the transmission of this stress to the operating nut 28 in a degree sufficient to cause the rotation of the shaft 17 and the 50 consequent closure of the plates.

From the foregoing it is believed to be obvious that a device of this character constructed in accordance with our invention is particularly well adapted for the purpose 55 for which it is intended by reason of the fact that it provides means for removing the glare from the headlights without destroying the illumination of the road at the front or road edge side of the vehicle and further- 60 more in that it provides a device which is readily operated, simple in construction and which may be readily installed. It will furthermore be obvious that the construction thereof as hereinbefore set forth is capable of some change and modification without materially departing from the spirit of our invention and we accordingly do not limit ourselves to the specific structure 65 thereof except as hereinafter claimed. 70

We claim:

In a shade device for the headlights of vehicles and in combination with a vehicle provided with headlights arranged adjacent opposite sides thereof, a plate associated 75 with each of the headlights, and means for shifting said plates to cover and uncover the lens openings of the headlights, one of said plates being provided in the lower marginal edge thereof with a notch permitting a portion of the rays of the headlight to pass downwardly and forwardly from the headlight, the other of said plates being provided with a notch permitting 80 passage of the rays of the headlight downwardly and forwardly and to that side of the headlight remote from the headlight bearing the first named plate. 85

In testimony whereof we hereunto affix our signatures.

PAUL S. SMITH.
W. L. SIMMONS.
ALBERT FORBES.
